[57] **CLAIM**

The ornamental design of an adjustable safety rail support bracket for a roof truss, as shown and described.

DESCRIPTION

FIG. 1 is a perspective view of an adjustable safety rail support bracket for a roof truss showing my new design; FIG. 2 is a side view thereof, the opposite side view being shown in FIG. 1;

FIG. 3 is an end view thereof;

FIG. 4 is an opposite end view thereof;

FIG. 5 is a top view thereof; and,

FIG. 6 is a bottom view thereof.

The broken line showing of fragmented structure is for illustrative purposes only and forms no part of the claimed design.
